C. W. DUNHAM.

RAILWAY SIGNALING.

APPLICATION FILED DEC. 27, 1919.

1,380,784.

Patented June 7, 1921.

UNITED STATES PATENT OFFICE.

CHARLES W. DUNHAM, OF FAIRMONT, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,380,784.

Specification of Letters Patent. Patented June 7, 1921.

Application filed December 27, 1919. Serial No. 347,748.

To all whom it may concern:

Be it known that I, CHARLES W. DUNHAM, a citizen of the United States, residing at Fairmont, in the county of Westmoreland and State of Pennsylvania, have invented 5 certain new and useful Improvements in Railway Signaling, of which the following is a specification.

My invention relates to electrical apparatus, and particularly to apparatus comprising a polarized relay, a circuit for such relay including a source of current and a pole-changer, and a second circuit controlled by the polarized relay.

One object of my invention is the provision of a novel means for reducing the interval of time during which the second circuit is open while the polarized relay is responding to a reversal of the pole-changer.

Apparatus embodying my invention is particularly well adapted to the control of signals and other devices for governing the passage of cars and trains along a railway, although it is not limited to such adaptation.

I will describe one form and arrangement of apparatus embodying my invention, and will then point out the novel features thereof in claims.

The accompanying drawing is a diagrammatic view showing a railway signaling system including a signal controlled in accordance with one form of my invention.

Referring now to the drawing, the reference characters 2 and 2^a designate the track rails of a railway over which traffic normally moves in the direction indicated by the arrow. The rails are divided by insulated joints 3 into a plurality of sections of 40 which only one complete section A—B is shown in the drawing. The section A—B is provided with a track circuit comprising as usual the track rails of the section, a battery 5 connected across the rails at the exit 45 end of the section, and a track relay 6 connected across the rails at the entrance end of the section.

Located adjacent the entrance end of the section A—B, is a signal S^b governing traffic through this section. This signal is controlled by a polarized relay R which, in turn, is controlled by the track relay 6 and by a pole-changer P operated by a signal

S^a at the entrance end of the section to the left of section A—B. The circuit for relay 55 R is from a battery C^a, through wire 7, pole-changer P, wire 8, contact 9 of track relay 6, wires 10 and 10^a, winding of relay R, wires 11^a and 11, pole-changer P and wire 12 to battery C^a. When signal S^a is in the 60 "stop" position, the polarity of the current supplied to relay R by battery C^a is such that polarized contact 32 of this relay is open, and this current I will term current of reverse polarity. When signal S^a is in 65 the "caution" or "proceed" position, the pole-changer P is in the opposite position, so that current of normal polarity is supplied to relay R and contact 32 of this relay then becomes closed. Obviously, when track 70 relay 6 is open, as shown in the drawing, relay R is deenergized, so that the front points of its neutral contacts 15 and 24 are open and the back points of these contacts 75 are closed.

The signal S^b comprises a semaphore 4 biased to the horizontal or "stop" position, an electric motor M for moving the semaphore to the inclined or "caution" position and to the vertical or "proceed" position, 80 and a holding magnet H for holding the semaphore in the two last-mentioned positions.

As shown in the drawing, section A—B is occupied by a car or train V, so that track 85 relay 6 is open and polarized relay R is deenergized. All circuits for the control of motor M and holding magnet H are, consequently, open so that the semaphore 4 of signal S^b is in the stop position. I will now 90 assume that the car or train V passes out of section A—B and into the section next to the left. Track relay 6 then closes and signal S^a moves to the stop position, so that current of reverse polarity is supplied to 95 relay R. The neutral front contacts of this relay then close, but the polarized contact 32 opens. Holding magnet H then becomes energized, the circuit being from battery C^b, through wire 14, front point of contact 100 15 of relay R, wires 16, 17 and 18, contact 19^a—19 operated by semaphore 4, wire 20, winding of magnet H, wire 21, contact 22 of track relay 6, wire 23, front point of contact 24, and wires 25 and 26 to battery C^b. 105 The operating motor M is also energized,

the circuit being from battery C^B , through wire 14, front point of contact 15, wires 16, 17 and 27, contact 28^a—28, wire 29, motor M and wires 30 and 26 to battery C^B . Motor M then operates to move semaphore 4 to its inclined or caution position at which point the circuit just traced for the motor is opened, because the wiper 28 passes off of contact segment 28^a. The signal is held in the caution position by magnet H, however, because wiper 19 still engages with contact segment 19^a.

When the car or train passes out of the section to the left of the section A—B, signal S^A will move to the caution position, thereby shifting pole-changer P, so that current of normal polarity will be supplied to the polarized relay R. Contact 32 of this relay then closes and the front points of the neutral contacts open momentarily, but for the present I will assume that this opening of the neutral front contacts does not cause magnet H to release the semaphore 4. A new circuit for motor M is then closed, which circuit is from battery C^B , through wire 14, front point of contact 15, wires 16 and 31, polarized contact 32, wires 33 and 35, contact 28^b—28, wire 29, motor M and wires 30 and 26 to battery C^B . Motor M then operates to move the semaphore toward the proceed position, magnet H being energized during the first part of such movement by the same circuit as before, that is, through contact 19—19^a. After the semaphore has moved a short distance, however, contact 19—19^b closes and contact 19—19^a opens, whereupon a new circuit for magnet H closes, passing from battery C^B through wire 14, front point of contact 15, wires 16 and 31, contact 32, wires 33 and 34, contact 19^b—19, wire 20, magnet H, wire 21, contact 22, wire 23, front point of contact 24, and wires 25 and 26 to battery C^B . When the semaphore reaches the proceed position, the wiper 28 passes off of the contact segment 28^b, so that the motor stops. The signal is held in this position by magnet H, however, because wiper 19 still engages with the contact segment 19^b.

When signal S^B is in the proceed or caution position and a car or train enters section A—B, the opening of track relay 6 causes the polarized relay R to be deenergized, so that all circuits for motor M and holding magnet H become opened and signal S^B then returns to the stop position.

As I have already pointed out, when signal S^B is in the caution position and the polarity of the current supplied to the polarized relay R is reversed, the front points of neutral contacts 15 and 24 are momentarily opened, and this action will cause magnet H to release the semaphore unless means are provided to prevent such action. As here shown, this is prevented by supplying cur-

rent to magnet H from battery C^A while the back points of contacts 15 and 24 are closed during the reversal of polarity. Assuming that signal S^B is in the caution position, and that pole-changer P reverses, the circuit for holding magnet H during the brief interval of time that the back contacts of relay R are closed, is from battery C^A , through wire 7, pole-changer P, wire 8, track relay contact 9, wires 10 and 36, back point of contact 24, wire 23, track relay contact 22, wire 21, magnet H, wire 20, contact 19—19^a, wires 18, 17 and 16, back point of contact 15, wires 37 and 11, pole-changer P, and wire 12 to battery C^A . It is, of course, understood that when pole-changer P reverses, the interval of time during which the circuit for relay R is open is very short, in fact only a small fraction of a second. It is also well understood that the characteristics of relay R and of the circuit in which it is included are such that when the pole-changer reverses, the time interval required for the back contacts of relay R to close is substantially the same as the time interval during which the circuit is open at the pole-changer. It follows, therefore, that when the pole-changer reverses, the back points of contacts 15 and 24 will close at substantially the instant the circuit is reclosed at the pole-changer, and so magnet H will be supplied with current from battery C^A practically the whole time that these back points are closed, that is, during a considerable portion of the time that the front points of the relay contacts are open. I have found that with the apparatus constructed and arranged in this manner magnet H may be of the ordinary non-slow-acting type instead of the slow-acting type which is usually necessary when a signal is controlled by a polarized relay.

Inasmuch as the control of the signal does not depend upon the front contacts of the polarized relay R being open for a brief period of time, it is obvious that it is possible to make this relay slow-acting. As is well understood a relay of this character is desirable in signaling systems of certain types, such, for example, as that known as absolute permissive block signaling.

It will be observed that the circuits for the holding magnet H pass through a contact of the track relay 6. The reason for this is to make the signal respond quickly when a train enters the section A—B. This is particularly desirable in the event that the polarized relay R is slow-acting. It will be seen, therefore, that by my invention I am enabled to retain all of the advantages of a signal with a quick-acting holding magnet and still eliminate the bobbing at caution and proceed positions and other objectionable features which have usually required a slow-acting holding magnet.

One important feature of my invention is that the desired result is accomplished without any additional circuit breakers upon the signal or the controlling relay through which the motor current must pass.

Although I have herein shown and described only one form and arrangement of apparatus embodying my invention, it is understood that various changes and modifications may be made therein within the scope of the appended claims without departing from the spirit and scope of my invention.

Having thus described my invention, what I claim is:

1. In combination, a circuit including a relay having front and back contacts, a source of current, and means for reversing the polarity of the current supplied to said relay by said source; a signal including a biased semaphore and a magnet for holding the semaphore against the biasing force, a second source of current, and means for supplying said magnet with current from said second source when the front contacts of said relay are closed and from said first source when the back contacts of the relay are closed.

2. In combination, a circuit including a relay having front and back contacts, a source of current, and means for reversing the polarity of the current supplied to said relay by said source; a signal including a biased semaphore and a magnet for holding the semaphore against the biasing force, a second source of current, and means controlled by the contacts of said relay for connecting said magnet with said second source of current when the front contacts are closed and for connecting said magnet with said circuit in multiple with said relay when the back contacts are closed.

3. In combination, a circuit including a relay having front and back contacts, a source of current, and means for reversing the polarity of the current supplied to said relay from said source; a second source of current, a signal, and means for supplying said signal with current from said second source when the front contacts of said relay are closed and from the first source when the back contacts of said relay are closed.

4. In combination, a section of railway track, a track circuit for said section, a line relay having front and back contacts, a line circuit controlled by said track circuit and including said line relay and a source of current, means controlled by traffic conditions in advance of said section for reversing the polarity of the current supplied to said line circuit by said source, a signal for said section, a local source of current for said signal, and means for connecting said signal with said local source when the front contacts of said line relay are closed and with

said line circuit in multiple with said line relay when the back contacts of the line relay are closed.

5. In combination, a section of railway track, a track circuit for said section, a line relay having front and back contacts, a line circuit controlled by said track circuit and including said line relay and a source of current, means controlled by traffic conditions in advance of said section for reversing the polarity of the current supplied to said line circuit by said source, a signal for said section including a biased semaphore and a magnet for holding said semaphore against the biasing force, a local source of current for said signal, and means for connecting said magnet with said local source when the front contacts of said line relay are closed and with said line circuit in multiple with said line relay when the back contacts of the line relay are closed.

6. In combination, a section of railway track, a track circuit for said section including a track relay, a line relay having front and back contacts, a line circuit controlled by said track relay and including said line relay and a source of current, means controlled by traffic conditions in advance of said section for reversing the polarity of the current supplied to said line circuit by said source, a signal for said section including a biased semaphore and a magnet for holding the semaphore against the biasing force, a local source of current for said signal, a circuit for said magnet including said local source of current and the front contacts of said line relay, and a second circuit for said magnet including the first-mentioned source of current and a front contact of said track relay and the back contacts of said line relay. 105

7. In combination, a section of railway track, a track circuit for said section including a track relay, a line relay having front and back contacts, a line circuit controlled by said track relay and including said line relay and a source of current, means controlled by traffic conditions in advance of said section for reversing the polarity of the current supplied to said line circuit by said source, a signal for said section including a biased semaphore and a magnet for holding the semaphore in opposition to the biasing force, a local source of current, a circuit for said magnet controlled by the front contacts of said line relay and a front contact of said track relay and including said local source of current, and means for connecting said magnet with said line circuit in multiple with said line relay when the back contacts of the line relay are closed. 115

8. In combination, a circuit including a relay having front and back contacts, a source of current, and means for reversing the polarity of the current supplied to said relay from said source; a second source of 130

current, a signal, a circuit for said signal including said second source of current and the front contacts of said relay, and a second circuit for said signal including the first source 5 of current and the back contacts of said relay.

9. In combination, a circuit including a relay having front and back contacts, a source of current, and means for reversing 10 the polarity of the current supplied to said relay by said source; a signal including a biased semaphore and a magnet for holding the semaphore against the biasing force, a second source of current, a circuit for said 15 magnet including said second source of current and the front contacts of said relay, and a second circuit for said magnet including said first source of current and the back contacts of said relay.

10. In combination, a circuit including a relay having front and back contacts, a source of current, and means for reversing 20 the polarity of the current supplied to said relay from said source; a second source of current, a signal including a semaphore 25 biased to one position, a motor for moving it to another position, and a magnet for holding the semaphore in the latter position; a circuit for said motor controlled by the front 30 contacts of said relay, and means for supplying said magnet with current from said second source when the front contacts of said relay are closed and with current from said first source when the front contacts of said 35 relay are open.

11. In combination, a relay having front and back contacts, a circuit for said relay in-

cluding a source of current and a pole-changer, a second circuit controlled by said relay, a second source of current, and means 40 for supplying current to said second circuit from said second source when the front contacts of said relay are closed and from said first source when the back contacts are closed.

12. In combination, a relay having front 45 and back contacts, a circuit for said relay including a source of current and a pole-changer, a magnet, a second source of current, a circuit for said magnet including said 50 second source and the front contacts of said relay, and a second circuit for said magnet including the first source of current and the back contacts of said relay.

13. In combination, a relay having front and back contacts, a circuit for said relay 55 including a source of current and a pole-changer, the elements in said circuit being so arranged and adjusted that when the pole-changer reverses, the back contacts of the relay close at substantially the same instant 60 that the circuit is re-closed at the pole-changer, a second circuit controlled by said relay, a second source of current, and means for supplying current to said second circuit from said second source when the front contacts of said relay are closed and from said 65 first source when the back contacts are closed.

In testimony whereof I affix my signature in presence of two witnesses.

CHARLES W. DUNHAM.
